Inventor:

G. K. Kelsea,

UNITED STATES PATENT OFFICE.

GEORGE K. KELSEA, OF DETROIT, MICHIGAN.

AXLE-BOX LID.

SPECIFICATION forming part of Letters Patent No. 433,987, dated August 12, 1890.

Application filed November 8, 1889. Serial No. 329,709. (No model.)

To all whom it may concern:

Be it known that I, GEORGE K. KELSEA, a citizen of Detroit, county of Wayne, State of Michigan, have invented a new and Improved 5 Railroad-Car Axle-Box Lid, of which the following is a specification, reference being had to the accompanying drawings.

The object of my invention is to provide an axle-box lid that can be easily attached to 10 the box, is strong, easily opened, will not remain open when the car is in motion, will not rattle, and is dust-proof.

The annexed drawings, to which reference is made, fully illustrates my invention.

15 Figure 1 represents a side elevation of the axle-box, showing position of knob. Fig. 2 is a front elevation showing shape of knobs. Figs. 3 to 5 show perspective views of the plate and rod of which the lid is composed, 20 Fig. 3 showing plate, Fig. 5 showing the rod separately, and Fig. 4 showing the two combined forming the lid. Fig. 6 is a perspective view of the lid attached and closed. Fig. 7 is a perspective view of the lid attached and open.

To illustrate more in detail, Fig. 3 shows 25 plate D bent up at the sides, having perforations *bb* therein, through which rod C is passed, as shown in Fig. 4. Fig. 5 shows rod as it is bent after having been run through perforations *bb* on plate D. It is then in shape 30 ready to be closed around knobs *aa* on the axle-box.

Having thus described my invention, what I claim, and desire to secure by Letters Patent, is—

35 In a car-axle box, the combination of the axle-box provided with knobs *aa*, with the lid having upturned sides and having perforations therein, and a rod passed through said perforations and clasped by its ends 40 around the knobs, substantially as described.

In testimony whereof I affix my signature in presence of two witnesses.

GEO. K. KELSEA.
